ABSTRACT OF THE DISCLOSURE

A cotton clogging-preventive device for continuous ringless spinning machines. The device has a rotary spinning chamber having a fiber collecting surface and operating under subatmospheric pressure. Rotary transfer bodies for transferring fibers are disposed between said rotary spinning chamber and the fiber feed part including a collector, and a casing surrounds said rotary transfer bodies and has an air inlet channel directed to the spinning chamber. Between said rotary transfer bodies and the casing wall there is provided in the casing wall an air inlet hole for admitting air from the outside.

The present invention relates to improvements in a continuous ringless spinning machine, which produces spun yarn directly from a sliver of staple fiber, such sliver being fed to a feed roller and combed by a combing roller peripherally provided with a saw tooth wire to separate and parallelize the fibers. The fibers are then introduced into a rotary spinning chamber having a subatmospheric pressure therein by a stream of air produced by said subatmospheric pressure and are centrifugally forced to adhere to a fiber collecting surface provided on the maximum inner diameter portion of said spinning chamber. The fibers thus adhere to the fiber collecting surface and are caught by the end of a twisted yarn leading from a package and are twisted while being successively rolled and withdrawn by the action of takeup rollers to form a spun yarn.

In the aforesaid ringless spinning machine, the rotary transfer bodies such as the feed roller and combing roller disposed between a fiber feed and the rotary spinning chamber have their lateral surfaces surrounded by the wall of a casing with a small clearance maintained therebetween short fibers tend to enter said clearance and accumulate therein. If the amount of accumulation increases too greatly, the rotating ability of the rotary transfer bodies decreases to detract from the quality of the spun yarn, or if the amount further increases, damage to the machine may result.

These disadvantages are attributable to the fact that the rotation of the rotary transfer bodies creates a subatmospheric pressure in the space between the rotary transfer bodies and the wall of the casing surrounding them so that short fibers tend to enter the space together with air.

Further, the aforesaid disadvantages are also attributable to the fact that on the side of the fiber feed, the feed roller surface and combing roller surface are closely adjacent to each other and in this condition the feed roller is rotating at a low speed while the combing roller is rotating at an extremely high speed so that in the region of adjacency between both rollers the air pressure becomes increased to the extent that air containing short fibers tends to enter the clearance between the feed roller and the wall of the casing surrounding the feed roller.

An object of the present invention is to eliminate the aforesaid disadvantages by providing one or more air in-

let holes in the wall of the casing surrounding the rotary transfer bodies disposed between the fiber feed and the rotary spinning chamber in order to allow air from the outside (ambient atmosphere) to flow into the clearance between said rotary transfer bodies and said casing wall so that the inflow air from said air inlet hole is introduced into the fiber transfer passageway.

Another object of the invention, in view of the fact that there is a phenomenon in which air-borne short fibers enter the clearance between the combing roller and the casing wall surrounding said combing roller as the high speed rotation of said combing roller creates a subatmospheric pressure in said clearance, is to provide a device for preventing such short fibers from entering said clearance, wherein the casing wall adjacent to the lateral surface of the combing roller is provided with an air inlet hole communicating with the outside.

A further object of the invention is to provide a fiber clogging-preventive device wherein the casing wall adjacent to the lateral surface of the feed roller is provided with an air inlet hole communicating with the atmosphere for precluding the phenomenon in which at a position where the high speed rotating combing roller and the low speed rotating feed roller approach each other, and under the influence of the rotation of the combing roller, air-borne short fibers enter the clearance between the feed roller and the casing wall surrounding the same and such short fibers accumulate therein.

Other objects and advantages of the invention will become apparent from the following description.

In the accompanying drawings:

FIG. 1 is a longitudinal section showing an arrangement according to the present invention for preventing the clogging of fibers at the lateral surface of a combing roller;

FIG. 2 is a fragmentary longitudinal section of the principal portion of FIG. 1, but illustrating a modified embodiment;

FIG. 3 is a cross-section view showing a feed roller and a combing roller and illustrating an arrangement embodying the present invention for preventing the clogging of fibers at the lateral surfaces of said rollers; and

FIG. 4 is a longitudinal section of principal portions of FIG. 3.

The invention will now be described with reference to the drawings showing embodiments thereof.

A plurality of feed fibers consisting of staple fibers collected by a collector 1 of a fiber feed part are delivered by a feed roller 3 under the control of a presser 2. The peripheral surface of a combing roller 5 peripherally provided with a saw tooth wire 4 is positioned peripherally adjacent to said feed roller 3 so that the fibers delivered from the feed roller 3 are combed by the saw tooth wire 4 under the influence of the high speed rotation of said combing roller 5 so that they are parallelized while being separated and are transferred to a rotary spinning chamber 8 via a working passageway 6.

A casing 7 has an air inlet channel 9 establishing communication between the rotary spinning chamber 8 and the atmosphere. Part of the peripheral surface of the combing roller is exposed to the central region of the air inlet channel 9. The fibers caught on the peripheral surface of the combing roller 5 are stripped therefrom by an air stream in the direction of arrow created in said air inlet channel 9 owing to the subatmospheric pressure in the spinning chamber 8 and are transferred to the spinning chamber 8 and collected on a fiber collecting surface 10. As the front end of a twisted yarn 16 leading from a package (not shown) reaches the fiber collecting surface 10 of the spinning chamber 8, the collected fibers are caught by the front end of the twisted yarn 16 and while being twisted, they are successively and continuously

drawn through an opening 11 and wound as a spun yarn.

Now, in the aforesaid ringless spinning machine, since the combing roller 5 rotates at a very high speed, the greater part of the lateral surface 13 thereof perpendicular to the axis of a rotary shaft 12 is recessed as shown in FIG. 1 to reduce the weight to a minimum, thus forming cavities 15 between the wall 14 of the casing 7 and said lateral surface 13.

During the operation of the spinning machine, the high speed rotation of the combing roller 5 causes the air in the cavities 15, thereby to be centrifugally discharged to creating a reduced pressure condition. However, as shown in FIG. 3, air communication between a return passageway 6' and the working passageway 6 is interrupted by the feed fibers at the fiber feed part, and the pressure in the return passageway 6' is consequently much higher than the pressure in the working passageway 6.

Stated in more detail, a comparison of the pressures in the working passageway 6, return passageway 6' and cavities 15, respectively, shows that, with reference to FIG. 3, approximately on the right-hand side of a line L interconnecting a working point B and a substantial fiber stripping point C on the combing roller 5, the pressure in the cavities 15 is higher than that in the working passageway 6 and that on the left-hand side of the line L, the pressure in the cavities 15 is lower than that in the return passageway 6'. Thus, if P_a and P_b represent the pressures in the passageways 6 and 6', respectively, P_c the pressure in the cavities 15, and P atmospheric pressure, then the following pressure relation is obtained:

$$P_a < P_c < P_b < P$$

Therefore, in the region approximately on the left-hand side of the line L, the air in the return passageway 6' flows into the cavities 15 and then the air in the cavities flows into the working passageway 6. The air flowing from the return passageway 6' contains a substantial amount of short fibers, which short fibers often accumulate in the cavities 15 and in the clearance between the lateral surface 13 of the combing roller 5 and the casing wall 14. Moreover, when the subatmospheric pressure condition of the fiber transfer passageway changes to an atmospheric condition as the operation of the spinning machine is stopped, there occurs a phenomenon in which short fibers enter said clearance and the cavities 15. That is, when the fiber transfer passageway resumes its atmospheric condition as a result of the stoppage of the spinning machine (the stoppage of the rotation of the rotary spinning chamber), the working passageway 6 and return passageway 6' first resume their atmospheric condition, followed by the cavities 15. At this time, therefore, air flows from the passageways 6 and 6' into the cavities 15 with the result that the short fibers and lint contained in said air are conveyed into said cavities 15. When the operation of the spinning machine is resumed and hence the combing roller 5 is rotated, the short fibers which have already entered cavities 15 are not smoothly discharged as they adhere to the cavities 15 or settle in the clearance between the casing wall 14 and the lateral surface 13 of the combing roller 5, thus assisting in short fibers adhering to and accumulating in said clearance, thereby hindering the smooth rotation of the combing roller 5, causing damages to the machine and detracting from the quality of spun yarn.

As shown in FIGS. 1 and 2, the present invention precludes this phenomenon of short fiber entry by providing an air inlet hole 17 in the wall 14 of the casing 7 to establish communication between the cavities 15 in the combing roller 5 and the atmosphere. Thus, although the air in the cavities 15 is discharged under the combined action of centrifugal force and fanning grooves 18 in the lateral surface of the combing roller 5 during the operation of the machine, the ambient air flows into said cavities 15 through the air inlet hole 17 owing to the pressure

difference, so that the degree of negativity of the pressure in the cavities 15 is alleviated and pressure relationship $P_a < P_c < P_b < P$ is improved to become $P_a < P_b < P_c < P$. As a result, the air stream directed from the return passageway 6' to the cavities 15 disappears and the phenomenon of short fibers entering the cavities also disappears. Further, in the case where the spinning machine is stopped, the pressure in the cavities first becomes atmospheric by the action of the air inlet hole 17, with the result that the flow of air from the passageways 6 and 6' disappears, thus making it possible to prevent short fibers from the passageways 6 and 6' from entering the cavities. Under the combined action of the centrifugal force on the combing roller 5 and inflow of air through the air inlet hole 17 occurring simultaneously with the restarting of the operation, the air stagnant in the cavities 15 is smoothly discharged to the working passageway 6 or return passageway 6' so that short fibers and lint will no longer stagnate in the cavities 15 and the clearance between the casing wall 14 and the lateral surface 13 of the combing roller 5.

The distribution of the subatmospheric pressure condition in the clearance between the lateral surface 13 and the casing wall 14 corresponding thereto is such that the degree of negativity of the pressure becomes higher toward the shaft 12 of the combing roller 5. Therefore, it is preferable that said air inlet hole 17 be disposed as close to the shaft 12 as possible. In this case it is desirable that the upper end of the shaft 12 be flush with the lateral surface 13 of the combing roller 5 and that the air inlet hole be disposed immediately opposite the end of shaft 12.

Further, in the ringless spinning machine shown in FIG. 3 wherein the feed roller 3 and the combing roller 5 are disposed adjacent each other within the casing 7, the space extending from a region of adjacency between the feed roller 3 and the combing roller 5 to a position B where a sliver is subjected to the opening and combing action of the combing roller 5 has poor circulation of air. Thus, the air tending to flow in the return passageway 6' in the direction of rotation of the combing roller 5 as a result of the high speed rotation of the combing roller 5 is substantially interrupted at said area of adjacency A, resulting in a tendency to increase the pressure in the portion of the return passageway 6' nearer to the area of adjacency A, thus making it easier for air to enter the cavities 15. Therefore, it is desirable that a suitable number of air inlet holes such as said air inlet hole 17 be additionally provided in the casing wall 14 to be disposed adjacent and along the return passageway 6'. This is advantageous since it is thereby made possible to hold back the air tending to enter the cavities 15. In this way the clogging of fibers at the lateral surface of the combing roller 5 can be prevented. On the other hand, however, the clogging of fibers also occurs in the clearance between the casing wall 14 and the lateral surface of the feed roller 3 close to the combing roller 5. That is, as previously described, in FIG. 3 the space extending from the area of adjacency A between the feed roller 3 and the combing roller 5 to the position B where a sliver is subjected to the action of the combing roller 5 has poor circulation of air, so that the air tending to flow in the return passageway 6' as a result of the high speed rotation of the combing roller 5 is substantially interrupted at said area of adjacency A, thereby increasing the pressure in the passageway 6'. Thus, the high speed rotation of the combing roller 5 acts to cause the air in the return passageway 6' to flow into the clearance under relatively low pressure between the lateral surface 19 of the feed roller 3 and the casing wall 14. Moreover, this tendency becomes further pronounced since the feed roller 3 is disposed in the direction of inertia force of the air moving in the return passageway 6'. In this case, a very small amount of fibers which are not stripped off at the previously stated stripping point C remain on the saw tooth wire 4 of the combing roller 5 passing through the return passageway 6'. These remaining fibers and the air-borne short fibers flow into

the clearance between the lateral surface 19 of the feed roller and the casing wall 14 and settle therein causing the clogging of cotton. As a result, it becomes difficult to control the rotation of the feed roller 3 and such remaining fibers sometimes come out in a lump to join the feed sliver and enter the working passageway 6, thus causing yarn breakage and defective yarn formation.

According to the invention, as shown in FIGS. 3 and 4, an air inlet hole 20 is provided in the casing wall 14 adjacent to the lateral surface 19 of the feed roller 3, thereby enabling air to flow in from the atmosphere to prevent the entry of fibers into said clearance.

Since the spaces including the working passageway 6, return passageway 6', etc. communicating with the spinning chamber 8 in a subatmospheric pressure condition established by the high speed rotation are under the influence of the subatmospheric pressure in the spinning chamber 8 and are, as a whole, in a subatmospheric pressure condition, air flows in through said air inlet hole 20 owing to the pressure difference relative to the atmospheric pressure to increase the pressure in the clearance between the lateral surface 19 of the feed roller 3 and the casing wall 14. Moreover, the air which has flowed in through the air inlet hole 20 flows toward and working passageway whose pressure is lower than the pressure in said clearance, thereby preventing the entry of lint and short fibers into said clearance.

The position where the air inlet hole 20 is bored is preferably a position where the feed roller 3 and presser 2 are close to each other, and by this selection it is also possible to prevent the clogging of fibers in the clearance between the presser 2 and the casing wall 14.

In the embodiments described above, some modes of the invention have been illustrated wherein the air inlet holes 17 and 20 are provided in both casing walls 14 and 14' adjacent to the respective lateral surfaces 13 and 19 of the combing roller 5 and feed roller 3, but either one of said casing walls 14 and 14' alone may be provided with such holes.

The invention may be embodied in other forms than said embodiments without departing from the scope of the invention defined in the appended claims.

What I claim is:

1. In a continuous ringless spinning machine including

a rotary spinning chamber having a fiber collecting surface therein and operating under subatmospheric pressure, a fiber feed having a collector, a feed roller and a combing roller for transferring fibers from said fiber feed to said rotary spinning chamber, each of said rollers having lateral edges, and a casing surrounding said feed roller and said combing roller and having lateral surfaces forming clearances with said lateral edges of said roller, said casing having an air inlet channel extending therethrough tangentially to said combing roller and directed toward said rotary spinning chamber; the improvement comprising at least one air inlet hole extending through said casing from the exterior thereof into said clearances.

2. The improvement claimed in claim 1, wherein said air inlet hole extends through said casing opposite said lateral edge of said combing roller.

3. The improvement claimed in claim 1, wherein said combing roller is mounted in said casing by a shaft, and said air inlet hole extends through said casing closely adjacent said shaft.

4. The improvement claimed in claim 1, wherein the periphery of said combing roller and the opposing surface of said casing form therebetween a passageway, and said air inlet hole extends through said casing adjacent said passageway between the area where said fibers are stripped from said combing roller and the area where said combing roller grasps new fibers.

5. The improvement claimed in claim 1, wherein said air inlet hole extends through said casing opposite said lateral edge of said feed roller.
